TOGGLE ACTION SELF-LOCKING WRENCH
AND/OR NONLOCKING PLIERS

Friedrich W. Lampe, Detroit, Mich.

Application March 28, 1946, Serial No. 657,806

4 Claims. (Cl. 81—84)

1

This invention relates generally to pliers, and has particular relation to toggle action pliers. More particularly, it relates to toggle action pliers, the jaws of which may be repeatedly opened and closed by limited movement of a movable handle. The conventional toggle action pliers provide jaws which enter into locking engagement upon closing the same.

In using a tool of this character, it is frequently desirable to repeatedly open and close the jaws thereof. Obviously, such repeated opening and closing may not be conveniently accomplished if upon closing the same they become automatically locked. When this occurs, said jaws must be unlocked by forcibly urging the handles of the pliers apart.

Quite often, it is necessary to use pliers of this nature in a position or in places where use of both hands to accomplish the unlocking thereof is not only inconvenient, but reduces considerably the amount of work accomplished by the operator. Furthermore, it is often desirable to repeatedly open and close the jaws without too great movement of the movable handle, thereby making it possible for an operator to use the pliers with one hand in a limited space.

Therefore, it is a primary object of this invention to provide pliers of this character on which an arcuately movable clip is conveniently accessible to the operator for changing over the pliers from automatically locking pliers to pliers which may be repeatedly opened and closed.

Another object of this invention is to provide such pliers with an antilocking device, which, although conveniently and accessibly located, is so positioned that in use it may not be inadvertently moved into position permitting the pliers to automatically lock as the jaws are closed.

Another object of the present invention is to provide pliers of the character described in which the movable jaw may be prevented from fully opening while the adjusting screw is turned to bring such jaw into adjusted position, thereby facilitating such adjustment. To accomplish this, a slideable latch is provided on the movable handle to limit the opening movement of the same and thereby the movable jaw against opening fully.

A further object of the present invention is to provide pliers of the character described, the jaws of which may be repeatedly opened and closed by a limited movement of a movable handle.

A still further object of the present invention is to provide in pliers of this type means for preventing misalignment between the end of the

adjusting screw and the shiftable link which controls the jaw setting.

A still further object of the present invention is to provide toggle action pliers in which the adjustment screw is frictionally held against inadvertent movement after the jaws have been placed in predetermined, adjusted position.

Further objects and advantages of my invention will be apparent from the description which follows when considered in connection with the accompanying drawings in which like numerals indicate like parts wherever shown and wherein:

Figure 1 is a view in side sectional elevation of toggle action pliers with the jaws in open position, illustrating the improvements of this invention.

Figure 2 is a side elevation of the pliers shown in Figure 1 with the jaws in closed position.

Figure 3 is a bottom view of the pliers illustrated in Figure 1.

Figure 4 is a section taken substantially on line 4—4 of Figure 2 illustrating the antilocking shield in operative position.

Figure 5 is a section taken substantially on line 5—5 of Figure 2 illustrating the latch for limiting the opening movement of the movable handle and thereby the movable jaw from opening fully.

In the figures, the main handle portion of the pliers is designated at 1. A second handle, which is movable, is indicated at 2. As will hereinafter become more clear, movement of this handle in a direction toward handle 1 effects closing of the jaws of the pliers.

This handle 2, which is formed of a U-shaped section of varying depth, receives the arcuately movable jaw 3 in the front end thereof, between its walls 4 and 5, and is secured thereto by means of a pin 6 extending through mating openings provided in said jaw and walls.

The opposite ear of jaw 3 is retained within the walls 7 and 8 of the U-shaped handle 1 by means of pin 9. In this position, jaw 3 is opposite jaw member 10 secured in the nose of handle 1 by welding or other suitable means.

Rearwardly of pin 6 in handle 2, link 11 is pinned at 12 to such handle. This pivot 12 acts as the fulcrum point for handle 2. The opposite end of link 11 is pinned at 13 to the extending ears of friction clip 14 which frictionally engages the adjacent small end 15 of adjusting screw 16. Such adjusting screw 16 is threadably contained within the annular, rear portion 17 of handle 1. Rotation of adjustment screw 16

effects movement of clip 14 and link 11.

This movement of link 11 serves to move handle 2, causing jaw 3 to rotate about pivot 9 for adjusting said jaw a predetermined distance from jaw 10.

A spring 18 is attached to lug 19 of the jaw 3 which lies between pivots 6 and 9, respectively, and to a depressed clip 20 provided in handle 1 and tends to maintain jaws 3 and 10 in an open position. In order to close the jaws against the action of spring 18, movable handle 2 is forcibly urged toward handle 1. This causes handle 2 to pivot at 12, effecting link 11 to move arcuately in a forward direction exerting a force, by way of handle 2, against pin 6. Inasmuch as the length of the effective lever arm, afforded by jaw 3, between pins 6 and 9, is greater than that between pivot 9 and lug 19, the jaws close. Movement of handle 2 continues until lug 21, on link 11 engages the inner surface of handle 2. At such time, pivot points 6 and 13 are in line, and pivot 13 has passed slightly beyond the line of such pivots. The jaws are then locked, due to the force exerted at pin 6 in the direction of the pivot points, resulting from the action of spring 18. When it is desired to unlock the jaws, the equilibrium may be broken by urging handle 2 away from handle 1. This moves pivot 12 out of line with pivots 6 and 13, permitting spring 18 to open the jaws.

As stated in the foregoing, it is frequently desirable to use the pliers in such manner that the jaws 3 and 10 may be repeatedly opened and closed without becoming locked. To prevent such locking, an antilocking spacer 22 adapted to be interposed between stop 21 and the inner surface of movable handle 2 is pivotally mounted at 23 on link 11 to be arcuately moved into position between stop 21 and the inner surface of the movable arm 2. A tab 24, outwardly directed from spacer 22, permits the operator to shift such spacer by means of a finger or thumb. Another tab 25 acts as a stop to prevent spacer 22 from moving past the stop 21 as it is shifted into position between the same and the inner surface of movable handle 2.

In order to facilitate adjustment of the movable jaw 3, latch member 26, mounted in handle 2 between pins 6 and 12, may be slidably moved into engagement with lip 27, provided therefor on link 11, as movable handle 2 is urged toward handle 1. Such engagement occurs while some movement of handle 2 toward handle 1 is still possible, that is to say, before the same is prevented by stop 21 or spacer 25. This engagement of latch 26 and lip 27 limits the movable handle, when released, from fully opening and it will be appreciated that jaw 3 is thereby prevented from moving fully away from jaw 10. The operator may then easily adjust the jaw 3 by means of screw 16 and it is possible with the remaining movement of handle 2 toward handle 1 to tightly grip an object between jaws 3 and 10, although screw 16 may have been turned inwardly until tight. Thus, by preventing full opening of the jaw 3, the operator is not required to unnecessarily open and close the jaws while adjusting jaw 3.

Movement of latch 26 into engagement with lip 27 is accomplished by means of rivet 28 which extends through the latch 26 for securing said latch to cover 29 exteriorly of handle 2. Rivet 28 is provided with a conveniently shaped head 30 which may be contacted by the operator's finger for shifting rivet 28 in groove 31 provided

therefor in handle 2. Movement of rivet 28, of course, moves latch 26 into or out of engagement with the lip 27 on the link 11.

This limited opening of handle 2 is also desirable when the pliers are used in one-handed operation or in places where full opening of handle 2 is either undesirable or impossible. With such limited opening of handle 2, all the advantages of permitting the jaws to be opened and closed repeatedly, at the will of the operator, are retained while the disadvantage of having handles 1 and 2 widely separated to accomplish opening of the jaws is eliminated.

In order to insure positive alignment between the reduced end 15 of adjusting screw 16 and the adjacent abutting end of link 11 at all times, clip 14 is provided with the annular collar 32. Such annular collar 32 is adapted to receive end 15 of such adjusting screw 16. Thus, with clip 14 pinned at 13 to the link 11, it will be appreciated that these two elements must remain in alignment. A further improvement is afforded by collar 32. This collar frictionally engages end 15 of screw 16. Such frictional engagement prevents rotation of adjustment screw 16 under normal handling of the pliers when such screw is touched by the operator. Positive rotation of such screw 16 is thereby required to change the setting of the jaws.

Thus, it may be seen that by providing toggle action pliers with the improvements described in the foregoing, it is possible to provide pliers of this character with antilocking means and with means to prevent full opening of the handle, allowing such pliers to be used with great ease in single-handed operation when it is desirable to repeatedly open and close the jaws of the same.

It will be clear from the foregoing description that the toggle action pliers shown in the drawings and described above have been illustrated and described in rather specific detail. Obviously, many modifications, changes, and departures from the above described construction may be made without departing from the generic spirit and scope of the invention as set forth in the subjoined claims.

What is claimed is:

1. Toggle action pliers comprising, a handle, a fixed jaw in one end thereof, a screw threadably retained in the opposite end of said handle, a friction clip having an annular portion adapted to frictionally engage an end of the screw, and a pair of arms extending from said annular portion, an arcuately movable jaw pivotally connected to said handle, a movable handle having side walls and being pivotally connected to said jaw, a link having one end pivotally connected between said arms extending from said friction clip, the other end of the link being pivotally connected between the side walls of the movable handle and forming a fulcrum therefor, a spring attached to said movable jaw and first named handle to arcuately move said movable jaw away from the fixed jaw, said movable handle overcoming the action of the spring to effect arcuate movement of the movable jaw toward the fixed jaw as said handle is forcibly urged toward said first named handle, a stop on said link adapted to engage the inner surface of the movable handle for preventing movement of said handle after a pivot connecting the same to said link passes slightly beyond the line of pivots connecting the same to said movable jaw and said link to the friction clip, and a spacer element pivotally mounted on said link and adapted to be inter-

posed between said stop and inner surface of the movable handle.

2. Toggle action pliers comprising, a handle, a fixed jaw in one end thereof, a screw threadably retained in the opposite end of said handle, a friction clip having an annular portion adapted to surround and frictionally grip an end of the screw, and a pair of spaced arms extending from said annular portion, an arcuately movable jaw pivotally connected to said handle, a movable handle having side walls and being pivotally connected to said jaw, a link having one end pivotally connected between said arms extending from said friction clip, the other end of the link being pivotally connected between side walls of the movable handle and forming a fulcrum therefor, said screw being rotatable to shift the fulcrum of the movable handle, said friction clip serving to prevent inadvertent rotation of the screw after the fulcrum is in adjusted position, a spring attached to said movable jaw and first named handle serving to urge the movable jaw away from the fixed jaw, said movable handle serving to overcome the action of the spring to effect arcuate movement of the movable jaw toward the fixed jaw as said handle is forcibly urged toward the first named handle, a stop member projecting from said link and adapted to engage the inner surface of the movable handle and limiting the movement of said handle after a pivot connecting the same to said link passes slightly beyond the line of pivots connecting said handle to said movable jaw and said link to the friction clip thereby locking the jaws in gripping relation with an object therebetween, a spacer element pivotally mounted on said link being adapted to be interposed when desirable between the stop member and the inner surface of the movable handle to increase the effective length of said stop member, and a shiftable latch on the movable handle cooperating with a lip on said link for limiting the opening of the handle when such latch is shifted to contact said lip.

3. Toggle action pliers comprising a handle, a fixed jaw in one end thereof, a screw threadably retained in the opposite end of said handle, a friction clip having an annular portion adapted to frictionally engage an end of the screw, and a pair of spaced arms extending from said annular portion, an arcuately movable jaws pivotally connected to said handle, a movable handle having side walls and being pivotally connected to said movable jaw, a link having one end pivotally connected between said arms extending from said friction clip, the other end of the link pivotally connected between the side walls of the movable handle and forming a fulcrum therefor, said screw being rotatable to shift fulcrum of the movable handle, said friction clip serving to prevent inadvertent rotation of the screw after the fulcrum is in adjusted position, a spring attached to said movable jaw and first named handle and serving to arcuately urge said movable jaw away from the fixed jaw, said movable handle serving to overcome the action of the

spring to effect arcuate movement of the movable jaw toward the fixed jaw as said handle is forcibly urged toward the first named handle, a stop member on said link adapted to engage the inner surface of the movable handle for preventing movement of said handle after a pivot connecting the same to said link passes slightly beyond the line of pivots connecting said handle to said movable jaw and said link to the friction clip thereby locking the jaws in gripping relation with an object therebetween, and a shiftable latch on the movable handle adapted to engage a lip on said link for limiting the opening of the handle to unlock said jaws.

4. Toggle action pliers comprising, a handle, a fixed jaw in one end thereof, a screw threadably retained in the opposite end of said handle, a friction clip having an annular portion adapted to frictionally engage an end of the screw, and a pair of spaced arms extending from said annular portion, an arcuately movable jaw pivotally connected to said handle, a movable handle having side walls and being pivotally connected to said movable jaw, a link having one end pivotally connected between said arms extending from said friction clip, the other end of the link being pivotally connected between side walls of the movable handle and forming a fulcrum therefor, said screw being rotatable to shift the fulcrum of the movable handle, said friction clip serving to prevent inadvertent rotation of the screw after the fulcrum is in adjusted position, a spring attached to said movable jaw and first named handle serving to arcuately urge said movable jaw away from the fixed jaw, said movable handle serving to overcome the action of the spring to effect arcuate movement of the movable jaw toward the fixed jaw as said handle is forcibly urged toward the first named handle, a stop member on said link adapted to engage the inner surface of the movable handle for preventing movement of said handle after a pivot connecting the same to said link passes slightly beyond the line of pivots connecting said handle to said movable jaw and said link to the friction clip, and an antilocking spacer adapted to be interposed between said stop and the inner surface of the movable handle to increase the effective length of said stop member, said spacer being shaped to enter protectively between the side wall of the movable handle.
